DOUBLE SPINNING TOP

Angelo Begood, New York, N. Y., assignor of one-half to Raphael Tacardon, New York, N. Y.

Application May 23, 1938, Serial No. 209,496

3 Claims. (Cl. 46—64)

This invention relates to new and useful improvements in a double spinning top.

More specifically, the invention proposes the construction of a double spinning top characterized by an axially elongated symmetrical body having its axial ends pointed so that the top may be spun on either end.

Still further it is proposed to provide the symmetrical body with an annular shoulder element which encircles the body in a plane at right angles to the axis thus forming an abutment to permit a cord to be wound upon the body for the purpose of spinning the top.

Still further it is proposed to provide the symmetrical body in the vicinity of the end formed with the shoulder with a cap axially slidably mounted upon the body and to form the cap with means for holding it in different fixed positions for exposing different amounts of the cylindrical portion upon which the cap is slidably mounted.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is an elevational view of a double spinning top constructed according to this invention.

Fig. 2 is a plan view looking in the direction of the line 2—2 of Fig. 1.

Fig. 3 is a sectional view of a double spinning top constructed according to a modification of the invention.

Fig. 4 is an enlarged sectional view taken on the line 4—4 of Fig. 3.

Fig. 5 is a fragmentary view of a portion of Fig. 3 but with the cap in the raised position.

Fig. 6 is a view similar to Fig. 1 but illustrating a still further modification of the invention.

The double spinning top, according to this invention, comprises an axially elongated symmetrical body 10 having its axial ends pointed. This body 10 may be constructed from wood or similar material and is provided at its pointed ends with pegs 11. The pegs are constructed from metal and have shank portions which engage into the body 10 for permitting the top to be spun on either end.

An annular shoulder element 10a encircles the body 10 in a plane at right angles to the axis thereof for forming an abutment for a cord 12 which is adapted to be wound upon the body 10.

The annular shoulder element 10a is formed integrally with the body 10 by cutting the same therein at the time the top is being formed.

The cord 12 is constructed with a gradually diminishing diameter and is adapted to have its small end wound upon the top and its large end held by the person spinning the top.

The operation of the top is as follows:—

The cord 12 is wound upon the top body 10 with its small end starting at the shoulder 10a. After the cord 12 has been completely wound upon the body 10 the large end is grasped in the hand and the top is thrown in the usual manner for spinning the same. The top body 10 may be held in the hand with either of its ends directed downwards for spinning the top on either end.

According to the modification shown in Figs. 3—5 an axially elongated symmetrical body 20 has its axial ends pointed. A shoulder element 20 encircles the body in a plane at right angles to the axis for forming an abutment for a cord 21. The cylindrical body 20 is formed from separate sections 20a and 20b which are co-axial. The section 20a is formed with a peg 22 upon which the body is adapted to rest when the top is spinning on this point. A similar peg 23 is formed upon the section 20b and has its shank portion extending into the section 20a for holding the section 20b in position upon the section 20a. This shank portion freely passes through an opening formed in the section 20b and is threaded into an opening formed in the section 20a.

The annular shoulder element comprises an annular ring element 24 which slidably engages a cylindrical portion 20aa formed on the end of the section 20a adjacent the section 20b. A cap element 25 engages over the section 20b and has its edge portion engaged into an upwardly extending flange 24a integrally formed with the ring element 24. The flange 24a is adapted to be welded, soldered or in any other manner fixedly attached to the bottom edge of the cap 25. At its apex end the cap 25 is formed with an opening through which the peg 23 extends.

Means are provided for holding the cap element in various fixed positions to expose different amounts of the cylindrical portion 20aa. These means comprise inwardly extending pegs 26 formed on the annular ring element 24 and which engage into bayonet slot 27 and are fixedly attached at one of their ends to the cylindrical portion 20aa. Springs 28 are formed in the arms of the bayonet slot 27 and are fixedly attached at one of their ends to the cylindrical element 25.

20^{aa} and are adapted to have their other ends releasably engage the pins 26 for holding the cap in fixed positions.

When the pins 26 are held in position by the 5 lower springs 28, the cap will be in the position illustrated by the full lines in Fig. 3. When the position of the pins is shifted so as to engage the top springs 28 the cap will be in a position illustrated by the dot and dash lines 25' in Fig.

10 3, or the full lines in Fig. 5.

When the cap element 25 is positioned closer to the peg 23 it is possible to wind a portion of the cord 12 upon the exposed portion of the cylindrical portion 20^{aa} positioning the cord closer 15 to the end of the peg 23 varying the amount of skill necessary to spin the top. If one becomes accustomed to spinning the top in the position shown in Fig. 3 and the position of the parts is shifted to that shown in Fig. 5 a greater amount 20 of skill will be required to spin the top.

According to the modification shown in Fig. 6 the top body 10 is constructed similar to the top shown in Fig. 1 except that the ends thereof do not have the pegs 11 attached thereto. In other 25 respects this form of the invention is similar to the previous forms and similar parts may be identified by corresponding reference numerals.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A double spinning top, comprising an axially elongated symmetrical body having its axial 40 ends pointed, and an annular shoulder element encircling said body in a plane at right angles to said axis for forming an abutment for a cord

wound about said body, said annular shoulder element comprising an annular ring slidably mounted on a cylindrical portion of said body, a cap element engaging over one end of said top body and being fixedly attached to said annular ring, said body bulging immediately adjacent said shoulder element, and means for holding said cap in different fixed positions to expose different amounts of said cylindrical portion. 5

2. A double spinning top, comprising an axially elongated symmetrical body having its axial ends pointed, and an annular shoulder element encircling said body in a plane at right angles to said axis for forming an abutment for a cord wound about said body, said annular shoulder element 15 comprising an annular ring slidably mounted on a cylindrical portion of said body, a cap element engaging over one end of said top body and being fixedly attached to said annular ring, said body bulging immediately adjacent said shoulder element, and means for holding said cap in different fixed positions to expose different amounts of said cylindrical portion, said means comprising inwardly extending pegs formed on said annular ring and engaging into bayonet slots formed 20 in the side of said cylindrical portion, leaf springs mounted within the arms of said bayonet slots and engageable against said pegs for holding said pegs in fixed position within the arms of said slot. 25

3. In a double spinning top, an axially elongated symmetrical body having its ends pointed, a cylindrical portion formed on said body intermediate of its ends, and an annular ring mounted on said cylindrical portion forming a shoulder 35 for a cord adapted to be wound upon said body, said ring being slidably mounted upon said cylindrical portion for changing the position of said shoulder with relation to the center of said top for varying the skill required to spin said top. 40

ANGELO BEGOOD.
